UNITED STATES PATENT OFFICE.

CLIFTON E. SINGLETON, OF BROOKLYN, NEW YORK.

FASTENING MEANS.

1,319,660.

Specification of Letters Patent.

Patented Oct. 21, 1919.

Application filed June 28, 1918, Serial No. 242,419. Renewed March 10, 1919. Serial No. 281,825.

To all whom it may concern:

Be it known that I, CLIFTON E. SINGLETON, a citizen of the United States, and a resident of the borough of Brooklyn, in the city of New York, county of Kings, and State of New York, have invented certain new and useful Improvements in Fastening Means, of which the following is a specification.

10 The present invention relates to fastening means, and more particularly of the character of fastening means employed in connection with cycles for supporting a member, such as a pump or the like, on the frame of the cycle.

15 The object of the invention is to produce a simple fastening means which can be readily applied to a support such as the frame of a cycle, and by means of which 20 a member can be conveniently and detachably carried on said support without producing a rattling noise.

25 To this end the invention consists of the features of construction, a preferred embodiment of which is hereinafter set forth.

Figure 1 is a view in elevation of a portion of a cycle frame with the device of the invention attached.

30 Fig. 2 is an enlarged view in elevation of the fastening means with the member to be supported partly in section.

Fig. 3 is a sectional view on the line 3—3 of Fig. 2.

35 Fig. 4 is a plan view of one of the helices used in connection with the fastening means.

1 indicates a support of any suitable character such as the frame of a cycle. 2 is a band of flexible material such as brass embracing said support and having at its free 40 ends the eyelets 3, the latter formed in this instance by doubling back said free ends between the band and the support. 4 is a helix resting with its base on the support and threaded through the eyelets of the 45 band. It will be understood that by turning the helix in one direction the ends of the band are drawn together thereby causing the band to clasp the support firmly. The helix 4 is of resilient material and cone-shaped as shown and is provided with an extension 5.

50 It will be understood that, when two or more of said fastening devices are placed in spaced relation as in Figs. 1 and 2, a mem-

ber such as the pump 6 may be suspended 55 by causing the extensions 5 to enter the openings 7 in the pump, and that the latter will be held firmly in such position and will not rattle when the cycle is subjected to 60 stresses.

I claim:

1. Fastening means comprising: a support, a band of flexible material embracing said support and having eyelets at its free ends, and a helix resting with its base on 65 said support and threaded through said eyelets for drawing the free ends of the band together.

2. Fastening means comprising: a support, a band of flexible material embracing 70 said support and having eyelets at its free ends, and a resilient helix resting with its base on said support and threaded through said eyelets for drawing the free ends of the band together.

3. Fastening means comprising: a support, a band of flexible material embracing 75 said support and having eyelets at its free ends, and a cone-shaped helix resting with its base on said support and threaded through said eyelets for drawing the free ends of the band together.

4. Fastening means comprising: a support, a band of flexible material embracing 85 said support and having eyelets at its free ends, and a cone-shaped resilient helix resting with its base on said support and threaded through said eyelets for drawing the free ends of the band together.

5. Fastening means comprising: a support, a band of flexible material embracing 90 said support and having eyelets at its free ends formed by doubling back said free ends between the band and the support, and a helix resting with its base on said support 95 and threaded through said eyelets for drawing the free ends of the band together.

6. Fastening means comprising: a support, two bands of flexible material spaced apart, each embracing said support and each having eyelets at its free ends, a helix associated with each of said bands resting with its base on said support and threaded through said eyelets for drawing the free 100 ends of the band together, a member to be supported, and extensions on said helices engaging and supporting said member.

7. Fastening means comprising: a sup-

port, two bands of flexible material spaced apart, each embracing said support and each having eyelets at its free ends, a resilient helix associated with each of said bands resting with its base on said support and threaded through said eyelets for drawing the free ends of the band together, a member to be supported having openings in its

ends, and extensions on said helices engaging within said openings and supporting 10 said member.

Signed at New York city, in the county of New York and State of New York, this 8th day of June, 1918.

CLIFTON E. SINGLETON.
